UNITED STATES PATENT OFFICE.

JAMES L. TRAINER, OF WEYMOUTH, MASSACHUSETTS.

WINDOW-AWNING.

1,191,371.

Specification of Letters Patent. Patented July 18, 1916.

Application filed September 15, 1914. Serial No. 862,255.

To all whom it may concern:

Be it known that I, JAMES L. TRAINER, a citizen of the United States of America, and a resident of Weymouth, in the county of 5 Norfolk and State of Massachusetts, have invented certain new and useful Improvements in Window-Awnings, of which the following is a specification.

This invention is an improvement in awnings and mechanism for attaching the same 10 to window casings or other structures.

The object of the invention is to provide an awning which is inexpensive to manufacture and which can be easily and quickly 15 attached to the building by the ordinary householder without the use of tools or the need of previous training. The various features employed to the accomplishment of this object will best be understood from the 20 following description and accompanying drawings of the preferred embodiment of the invention.

Of the drawings: Figure 1 represents a front elevation of the improved awning attached to a window casing. Fig. 2 represents a section on the line 2—2 of Fig. 1. Fig. 3 represents a sectional view looking upwardly into the awning, and Fig. 4 represents a detail showing the manner of 30 attaching the cords to the awning.

Similar characters designate like parts throughout the several figures of the drawings.

The canvas or other fabric 10 is cut in 35 the usual form and is secured along the bottom edge to a rod 11 bent to form three sides of a rectangle the ends of which are pivotally secured to the window casing so that the awning may be folded when not in 40 use. The upper edge of the canvas is permanently attached to a strip 12 preferably of wood which extends throughout the length of the awning and is provided with means for securing it to the window casing 45 13.

In the illustrated form of the invention the canvas is cut with an extension 14 which is fastened to the back of the strip 12 so that the canvas turns over the top of 50 the strip thereby concealing the strip from view from the outside. The strip 12 may be attached to the casing by providing holes 15 therein to receive screw eyes 16. The holes are elongated so that the strip can 55 be shoved over the screw eyes which have been previously fastened to the casing. The

screw eyes project sufficiently to allow a part of the eye to project through the strip to receive a fastening device such as the hooks 17 mounted on the strip. The strip 60 also carries two or more pulleys 18 to receive cords 19 by which the awning is raised.

The rod 11 is provided with an outwardly turned foot 20 at each end which is constructed to engage a screw eye 21 by springing the ends of the rod together and then allowing the ends to spread under the natural resiliency of the rod by which it is securely held in engagement with the eyes.

The cords 19 are operatively connected 70 with the awning by means of a tab 22 of heavy canvas or other comparatively strong material which has one end secured to the awning fabric near the rod 11 by stitches 23. The free end of the tab carries a gromet 24 75 through which the cord is affixed by whipping or otherwise as shown in Fig. 4.

A small window awning has been employed as an example in the elucidation of this invention, but it is evident that the 80 same feature of construction may be extended or enlarged to adapt the awning to use on piazzas, store windows and the like. One advantage of this awning is in the small 85 number of fixtures requiring permanent attachment to the house. For an ordinary window there are but four screw eyes required which reduces the defacement of the woodwork to a minimum and facilitates the original erection of the awning. When an 90 awning is to be removed for the winter with the purpose of replacing it in the spring, the screw eyes need not be removed as they can be so placed as not to interfere with blinds or shutters. All the labor of removing the 95 awning consists in disengaging the hooks 17 and springing the ends of the rod 11 together so as to free it from the screw eyes 21. When the awning is stored there are no 100 loose parts, screws, and so forth, to become lost and necessitate replacement.

It is to be understood that the invention is capable of variation within the skill of a mechanic without departing from the scope of the invention as defined by the claim.

It is believed that the advantages of an awning constructed in this manner will be fully apparent from the foregoing description.

Having thus described my invention, I 110 claim:

An awning having a rigid strip perma-

nently secured to and extending throughout the length of the upper inside edge of the awning fabric, the strip having openings extending therethrough beneath the fabric, fastening means adapted to be permanently attached to a building and extending through the openings with their ends protected by the fabric, and securing means en-

gageable with the fastening means beneath the fabric.

10

Signed by me at 4 Post Office Sq., Boston, Mass., this 8th day of September, 1914.

JAMES L. TRAINER.
